UNITED STATES PATENT OFFICE

LOUIS F. HAGEMANN, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO, CANADA

AUTOGRAPHIC REGISTER

Application filed November 20, 1923. Serial No. 675,802.

This invention relates to improvements in autographic registers and with respect to its more specific features to registers utilizing as supplies, books or pads composed of reversely 5 folded strips having form-registering apertures.

An object of this invention is to improve the register structurally and functionally to secure greater ease of manipulation, accuracy 10 of operation and ease of manufacture.

Other objects of the invention will be in part obvious and will in part appear herein-after.

The invention accordingly comprises the 15 features of construction, combinations of elements, and arrangement of parts, which will be exemplified in the construction hereinafter set forth and the scope of the application of which will be indicated in the claims.

20 For a fuller understanding of the nature and objects of the invention, reference should be had to the following detailed description taken in connection with the accompanying drawing, in which:

25 Figure 1 is a top plan view of a register embodying the invention.

Fig. 2 is a longitudinal section,

Fig. 3 is a transverse section through the feeding mechanism,

30 Fig. 4 is a detail of a portion of the sheet registering mechanism in cross-section,

Fig. 5 is a fragmental top plan of the sheet registering mechanism,

35 Fig. 6 is a fragmental side elevation of the tablet and carbon retaining mechanisms,

Fig. 7 is a fragmental section showing the relation of the cover plate to the carbon sheets, and

40 Fig. 8 is a detail section through the feed roll.

In the present embodiment of the invention, a case 1 is provided of any suitable capacity and of any desired material, the said case is provided at one end with a door 2 hinged at 45 3 to the bottom of the case. The case comprises three compartments, namely compartment 4 for a paper strip supply 5 of unused forms, a compartment 6 for the feeding mechanism and a compartment 7 for the permanent record strip.

A tablet 8 is arranged above the compartment 4. It is preferably hinged as at 9 to a rod 10 extending between the side walls of the machine. Suitable lugs 11 may extend inwardly from the side walls to furnish a support for the tablet when it is swung down into writing position. This tablet 8 is provided with suitable notches 12 to permit the feeding mechanism to extend upwardly through the tablet to engage sheets resting 55 upon it.

The feeding mechanism comprises a plurality of discs 13 rigidly mounted upon a shaft 14 journaled at the side walls of the case as shown at 15. This shaft extends outwardly 60 as shown at 16 beyond the side walls, an amount sufficient to receive a crank or handle 17. A ratchet wheel 18 is also rigidly fastened upon the shaft 14 and is adapted to co-operate with a spring pressed pawl 19 to prevent reversed rotation in the shaft. A cross bar 20 is mounted immediately above the discs 13 and carries a roll 21 in position to bear against said discs. In order to permit this cross bar and roll to be swung out of the way 70 for the purpose of inserting sheets beneath it, it is pivoted at one end as shown at 22 to a lug 23 on the side wall of the casing. At its other end, the cross bar is provided with an overhanging catch 24 adapted to pass beyond and be engaged by a latch 25 upon the other side wall of the casing. This latch is preferably 75 spring pressed and as illustrated, comprises a pin 26 slidably mounted in a recess 27 of the casing and rigidly secured to a small plate 28. 80 A pin 29 also rigidly attached to the said plate carries at its outer end a press button 30 while a spring 31 surrounding the pin 29 is lodged in a recess 32 in the side wall, engages at one end the button 30 and at the other 85 end, the end of the recess so that it urges outwardly the pin 29 and thereby the latch 25.

The roll 21 is journaled in blocks 33 which are slidably mounted for downward movement in recesses 34 in the cross bar 20, and 90 springs 35 urge those blocks downwardly. Detent screws 36 may be provided to prevent the blocks 33 from leaving the recesses 34.

With the construction just described, when the cross bar 20 is brought into position and 100

latched, the roll 21 will be spring pressed downwardly against the discs 13.

A cover plate 37 is hinged as at 38 to one of the side walls so that it may be swung into position to cover the compartment 7. This cover plate 37 is of sufficient length so that its forward end projects over the tablet 8 and under the cross bar 20, but space will be provided between it and the tablet to permit the permanent record sheet to pass between them and space will also be provided between the cross bar and the projecting end of the cover plate to permit the detachable record sheets to pass between them. In this manner the forward end of the cover plate serves as a separator as shown at 39 between those strips which are to be permanently retained in the machine and those which are to be removed.

By reason of the fact that the cross bar 20 extends over the projecting end of the cover plate 37, the cover plate cannot be lifted to open the compartment 7 until the cross bar has been released. It is thus possible to lock the compartment 7 and the feeding mechanism itself by locking the cross bar latch. As illustrated a suitable lock 40, operable by a key 41 has a locking pin 42 which may be projected into the pathway of the plate 28 to prevent the retraction of the latch 25.

The paper strip supply 5 is preferably in the form of an interfolded zigzag pad in which a number of strips, which may correspond to the number of copies of record desired, are superposed in registry and folded zigzag upon each other. The strips coming from the pad are carried from the writing tablet to the feeding mechanism. At the point where they pass over the tablet, a plurality of carbon sheets 43 are provided which may be interposed between the strips to transfer the record from the upper strip to the lower. As illustrated, a housing 44 on one of the side walls is recessed as at 45 to provide a pocket for a roll of transfer material. This roll may be composed of as many strips of transfer material rolled together as it is desired to make duplicate copies of the original record.

A second cover plate 46 is hinged as at 47 in position to be swung over the tablet 8 after the strips and carbon sheets have been disposed thereon. This second cover plate is recessed as at 48 to expose the form printed on the strip for inscription. A latch 49 is pivoted at 50 to the cover plate 46 and has an opening 51 adapted to engage a lug 52 upon the side wall to retain the cover plate in place. A handle 53 upon the latch permits its operation and at the same time assists in over-balancing it so that it is normally biased in a closed position.

Means are provided for separating the paper strips just before they pass over the writing tablet 8. As illustrated, a plurality

of rods 54, 55 and 56 extend from one side wall to the other to provide passageways between them for the reception of the strips and on those rods as 55 and 56, are pivoted guide plates 57 and 58, each of which is adapted to extend beyond and guide the superposed strip over the rod adjacent to it. The cover plate 46 carries upon its under surface a spring finger 59 in position to press downwardly upon the superposed strips just before they pass over the writing tablet 8 for the purpose of placing a slight tension upon the sheets, and the guide plates 57 and 58 are of such a length and so positioned that they maintain the different strips separated at the point opposite the spring finger 59 whereby the tension of the spring finger exerts an equal and independent pressure upon each strip so that the tension for one strip is, in so much, independent of that for the others.

The under side of the cover plate 46 is also provided with lateral ribs 60 adapted to press the carbon sheets toward the tablet 8 beyond the lateral edges of the record strips.

The machine is intended and is preferably used with record strips having printed forms thereon and having control apertures bearing definite relation to the printed form, and the lateral position of the discs corresponds to the lateral position of the control apertures. In this manner the rotation of the feeding discs will continue to advance the strips until the point of contact between the discs and the roll 21 comes opposite an aperture, whereupon the feeding will cease, thus the length of feed of the strip is controlled by the position of the apertures in the strip. With a mechanism of this kind, means are provided for starting the feeding operation at the beginning of each printed form. As illustrated, this comprises lugs 61 projecting inwardly from the feed discs and adapted to press upwardly upon the strips against the roll 21. The discs 13 have a slightly greater circumference than the length of the printed form with which the device is to be used, and the feeding operation being started by the lug 61 is continued by the discs 13 as soon as the aperture of the strip is passed and until the next aperture is reached, whereupon the feeding of the strips automatically ceases, to be started again only when the lugs 61 again come in contact with the strip.

In order to insure the initial registry of the forms, a web threading pin 62 is mounted in a recess in the discs 13 and is urged automatically outwardly thereof into web threading position by a spring 63, and this pin is positioned adjacent to the lugs 61, whereby at the time the feeding operation is about to be initiated by the lugs 61, the pin 62 will have been transversely projected outwardly of the disc 13 and is in registry with the apertures in the printed form and in en-

gagement with the roll 21. The spring 63 is of sufficiently slight tension so that the depression of the roll 21 by the springs 35 is capable of forcing the pin 62 down even or flush with the level of the discs 13 so as to be out of web threading position. For the purpose of keeping the pin 62 thus depressed, a circular cam 64 concentric with the disc engages a pin 65 upon the pin 62, but this cam or track is provided with a slot 66 to permit the pin 62 to be projected at the start or closing of the feeding operation. By reason of the spring 63, the pin 62 is projected out of its recesses whenever the cross bar 20 is raised provided the feed disc is in proper position to enable the pin 65 to pass through the slot 66, and the relative width of the slot 66 and pin 65 is such that the feeding handle cannot be moved with the pin 62 projected by reason of the engagement of the pin 65 with the sides of the slot 66.

The pin 62 is designed to serve the purpose of facilitating the initial registering of the sheets and during normal operation it is held depressed at the initial point by engagement with the roll 21 and during the rest of the feeding operation by engagement of the pin 65 with the circular pin restraining track, or cam 64.

The cam piece 64 is concentric with shaft 14, and the pin 100 is threadedly fixed to the cam piece and engages an aperture 101 in the frame side 1, to hold the cam piece 64 from turning, all as clearly illustrated in Fig. 5 of the drawing.

For the purpose of refolding the permanent record sheet within the compartment 7, a finger 67 is pivoted to the under side of the cover plate 37. The cover plate 46 is provided with a lug 68 in position to overlie the upper end of the end wall 2 and keep the compartment 4 closed.

For many purposes it is desirable to stop the feed handle at the completion of the feeding operation, and for this purpose a pin 69 is slidably mounted on the side of the casting and pressed outwardly by a spring 70 in a position to obstruct the turning of the handle when the feeding operation has been completed. In order to start a new feeding movement, this pin will first be pressed manually inward to release the handle.

With the machine as thus described, the various strips from the paper strip supply 5 are carried through their paper guides and over the tablet 8 one at a time and impaled or threaded upon the pin 62. As each strip is laid over the tablet, its corresponding transfer sheet is passed over it transversely 60 extending laterally far enough beyond the edge of the machine to be caught by the lug 52 and latch 49 when the cover plate 46 is lowered.

The lowermost strip is carried into the compartment 7 and serves as the permanent rec-

ord strip. The remaining strips are carried over the cover plate 37. When the strips are in position the cross bar 20 is carried down and latched and the latch locked by means of the key 41. Thereafter access cannot be had to the interior of the compartment 7 or to the record kept therein except by unlocking the compartment with a key. The cover plate 46 is now brought into place and the latch 49 closed to retain the cover plate in place and to retain the ends of the carbon sheets.

With the machine as thus prepared, the turning of the handle 17 will advance the sheets by reason of the fact that the sheets are gripped between the lugs 61 and the roll 21, and before the lug 61 passes out of engagement with the strips, the aperture of the strip has passed beyond the point of engagement between the discs 13 and the roll 21 so that the feeding is continued until the next aperture is reached by the discs. The lowermost sheet is advanced into the compartment 7 and there folded upon a pile in zigzag formation while the other sheets pass above the cover plate 37 and lie upon it with their lower edges opposite the edge of the cross bar 20. There they may readily be removed by tearing them on the edge of the cross bar.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:—

1. In an apparatus of the character described, in combination, a rotatable feed disc and co-operative presser between which a web is adapted to be frictionally gripped and fed, means adapted to rotate said disc, a rotative web registering pin with which web apertures are adapted to engage and co-operate to position the web in the apparatus for web feed, means adapted to move said pin into and out of web registering position, means adapted to lock said disc against feed movement, and means whereby the position of said pin determines the locking or unlocking effect of said locking means.

2. In an apparatus of the character described, in combination, a rotatable feed disc and a co-operative presser movable toward and from said disc and between which the

web is adapted frictionally to be gripped and fed, means adapted to rotate said disc, a rotative web registering pin, with which web apertures are adapted to engage and co-operate to position the web in the apparatus for web feed, arranged to be held out of registering position by said presser when said presser is in web gripping relation to said disc, and means, adapted to move said pin into web registering position, including a device automatically operative at a point in the rotation of said pin to so move said pin when the gripping pressure between said disc and presser is relieved.

15 3. In an apparatus of the character described, in combination, a rotatable feed disc and a co-operative presser movable toward and from said disc and between which the web is adapted frictionally to be gripped and fed, means adapted to rotate said disc, means adapted to lock said disc against feed movement, and means whereby the establishment of feed grip between said disc and presser causes unlocking effect of said locking means 25 in respect to said disc.

4. In an apparatus of the character described, in combination, a rotatable feed disc and a co-operative presser movable toward and from said disc and between which the web is adapted frictionally to be gripped and fed, means adapted to rotate said disc, a rotative web registering pin, with which web apertures are adapted to engage and co-operate to position the web in the apparatus for web feed, arranged to be held out of registering position by said presser when said presser is in web gripping relation to said disc, and means adapted to co-operate with said pin to lock said disc against feed movement while said pin is in web registering position and until moved out of registering position by said presser, and means adapted, on the movement of said pin out of registering position, to cause unlocking effect of said locking means.

45 5. In an apparatus of the character described, in combination, a rotatable feed disc and co-operative presser between which a web is adapted to be frictionally gripped and fed, means adapted to rotate said disc, a web registering pin movable transversely of the web into and out of web registering position and spring pressed into contact with said presser adjacent the line of grip on the web unless restrained by the interposed web.

6. In an apparatus of the character described, in combination, a rotatable feed disc and co-operative presser between which a web is adapted to be frictionally gripped and fed, means adapted to rotate said disc, a web registering pin movable transversely of the web into and out of web registering position and spring pressed into contact with said presser adjacent the line of grip on the web unless

restrained by the interposed web, said presser being movable into and out of web gripping relation to said disc, and manual actuated means for holding said presser in and releasing it from web gripping relation.

7. A device of the character described comprising in combination, a writing tablet, means for supporting a supply of continuous strips having apertures therein for the control of the feeding operation and having printed forms thereon in definite relation to said control apertures, means for feeding said strips over said tablet including two elements adapted to engage the web between them, one of said elements being movable from depressed feed position to position to open the feeding mechanism to expose the web, and a pin movable into and out of the pathway of said web in alignment with said control apertures and so positioned relative to said tablet that when a control aperture is impaled upon said pin, said printed forms will bear definite relation to said tablet, said pin being positively held depressed at all times excepting while said feeding mechanism is open.

8. In an apparatus of the character described, in combination, web feeding mechanism including a rotatable feed disc and co-operative presser between which a web is adapted to be frictionally gripped and fed, a reciprocal web registering pin, and means whereby actuation of said feeding mechanism is adapted to cause said pin to move toward said presser at intervals, including a spring for thrusting said pin toward said presser, said presser being manually movable to co-operate to move said pin, in the opposite direction to that engendered by said spring, at a predetermined point in the rotation of said disc.

9. In an apparatus of the character described, in combination, web feeding mechanism including a rotatable feed disc and co-operative presser between which a web is adapted to be frictionally gripped and fed, a reciprocal web registering pin, and means whereby actuation of said feeding mechanism is adapted to cause said pin to move toward said presser at intervals, including a spring for thrusting said pin toward said presser, said presser being manually movable to co-operate to move said pin, in the opposite direction to that engendered by said spring, at a predetermined point in the rotation of said disc, and manually releasable means adapted operatively to retain said presser in feed relation with said disc against thrust of said spring.

10. In an apparatus of the character described, in combination, web feeding mechanism including a rotatable feed disc and co-operative presser between which a web is adapted to be frictionally gripped and fed, a

reciprocal web registering pin, means whereby actuation of said feeding mechanism is adapted to cause said pin to move toward said presser at intervals, including a spring for thrusting said pin toward said presser, said presser being manually movable to cooperate to move said pin, in the opposite direction to that engendered by said spring, at a predetermined point in the rotation of said disc, manually releasable means adapted operatively to retain said presser in feed relation with said disk against thrust of said spring, and means including a track adapted to cooperate to prevent said thrust movement of said pin by said spring between the intervals of said thrust movement toward said presser, when said presser and disc are retained in said feed relation.

11. In an apparatus of the character described, in combination, feed rolls having approaching and receding movement relative to each other, a strip registering pin rotatable with one of said rolls and radially projectable and retractable, and means whereby feed rotation of said last mentioned roll is dependent on said pin being in retracted position.

12. In an apparatus of the character described, in combination, feed rolls having approaching and receding movement relative to each other, a strip registering pin rotatable with one of said rolls and radially projectable and retractable, and means whereby arrest of feed rotation of said last mentioned roll is adapted to be controlled by the position of said pin.

13. In an apparatus of the character described, in combination, feed rolls having approaching and receding movements, relative to each other, latching mechanism automatically operated by said approaching movement to retain said rolls in feed cooperative relation to each other, a registering pin rotatable with one of said rolls past the other roll and radially projectable and retractable, a spring biasing said pin for projecting movement, and a stationary member cooperative to hold said pin retracted between successive projected positions.

14. In an apparatus of the character described, in combination, feed rolls having approaching and receding movements relative to each other, latching mechanism automatically operated by said approaching movement to retain said rolls in feed cooperation relative to each other, a registering pin rotatable with one of said rolls past the other roll and radially projectable and retractable, a spring biasing said pin for projecting movement, and a stationary member cooperative to hold said pin retracted between successive projected positions, a casing having a cover movable to open and closed positions, and means whereby said latching of said rolls in

cooperative feed relation is adapted to hold said cover closed.

15. In an apparatus of the character described, in combination, feed rolls having approaching and receding movements relative to each other, latching mechanism automatically operated by said approaching movement to retain said rolls in feed cooperative relation to each other, a registering pin rotatable with one of said rolls past the other roll and radially projectable and retractable, a spring biasing said pin for projecting movement, a pin projecting from said registering pin, and a stationary track with which said projecting pin is adapted to coact to hold said registering pin in retracted position during rotation with said roll.

16. In an apparatus of the character described, in combination, feed rolls having approaching and receding movements relative to each other, latching mechanism automatically operated by said approaching movement to retain said rolls in feed cooperative relation to each other, a registering pin rotatable with one of said rolls past the other roll and radially projectable and retractable, a spring biasing said pin for projecting movement, a pin projecting from said registering pin, and a stationary track with which said projecting pin is adapted to coact to hold said registering pin in retracted position during rotation with said roll, said track having a slotted portion adapted to arrest rotation of said roll by engagement with said projecting pin.

In testimony whereof I affix my signature.
LOUIS F. HAGEMANN.
